UNITED STATES PATENT OFFICE.

GEORGE B. ROWE, OF OKLAHOMA, OKLAHOMA.

NEEDLE-THREADER.

1,274,786.

Specification of Letters Patent. Patented Aug. 6, 1918.

Application filed February 14, 1918. Serial No. 217,088.

To all whom it may concern:

Be it known that I, GEORGE B. ROWE, a citizen of the United States, residing at Oklahoma, in the county of Oklahoma and 5 State of Oklahoma, have invented certain new and useful Improvements in Needle-Threaders, of which the following is a specification.

This invention relates to devices for 10 threading the needles of sewing machines, and has for one of its objects to simplify and improve the construction and increase the efficiency and utility of devices of this character.

15 Another object of the invention is to provide a simply constructed device which may be readily adjusted without structural change to needles of various sizes and to sewing machines having various forms of 20 presser feet and needle bars.

With these and other objects in view, the invention consists in certain novel features of construction, as hereinafter shown and described and then specifically pointed out 25 in the claims; and in the drawings illustrative of the preferred embodiment of the invention—

Figure 1 is a front elevation of the improved device together with a portion of the 30 needle bar, the needle, and a portion of the presser foot with the improved device applied.

Fig. 2 is a rear elevation of the improved device.

35 Fig. 3 is a vertical section on the line 3—3 of Fig. 1.

The improved device comprises a body portion 10 having a longitudinally directed socket or seat 11 to receive the needle, the 40 latter represented conventionally at 12, and coupled in the ordinary manner in the socket portion 13 of the needle bar. Projecting from the body 10 near its lower end is a stop pin 14, the stop pin being so located as to support the needle in position 45 and assist in locating the needle in the seat 11. 15 represents a holding spring secured by a clamp screw 16 to the body 10, and extending over the face of the socket 11 and 50 operating to hold the needle yieldably in position in the socket.

Formed through the lower end of the body 55 is a thread receiving or guiding recess 17 converging from all sides toward one end and terminating in a relatively small downwardly opening aperture or recess 18 which

corresponds substantially with the eye 19 of the needle, the latter being so arranged within the socket 11 as to locate the eye 19 of the needle in transverse alinement with the 60 reduced terminal 18 of the recess. Attached to the lower face of the body 10 is a yieldable plate 20 which forms a yieldable closure to the reduced portion 18 of the recess, but which will yield to permit the releasing of 65 the thread from the device, as hereafter explained.

Threaded into the upper end of the body 10 is an adjusting screw 21 having a relatively large head 22 adapted to engage the 70 lower face of the needle socket portion 13 as shown in Fig. 1. By adjusting the screw 21 the body and its aperture 18 may be so arranged as to locate the eye 19 of the needle exactly opposite the aperture 18 of the 75 recess 17. The body 10 is provided with an outwardly opening recess 23 communicating with the threaded socket for the screw 21, so that the lower end of the screw is constantly visible from the outside. The position of the eye 19 varies with different sized 80 needles, and a scale is formed on the body 10 alongside the opening 23, to correspond to needles of varying numbers or sizes, and by noting the position of the screw 21 with relation to the lines of the scale, the body 10 may be adjusted to bring the eyes of needles of various sizes in proper position as will be obvious. The screw 21 is also provided 85 with a milled jam nut 24, so that the screw 90 may be rigidly supported in its adjusted position. Tapped through the body 10, preferably between the spring holding member 95 15 and the pin 14, is another adjusting screw 25 having a screw-driver receiving head 26. The screw 25 may thus be readily adjusted in the body, and is designed to bear by its free end against the body portion 27 of the 100 presser foot. By adjusting the screw 25 the location of the body 10 and its attachments 105 relatively to the presser foot may be maintained, so that the body may be exactly located in position. The screw 25 is provided with a milled jam nut 28 to hold the screw 25 in adjusted position and prevent accidental displacement.

The adjusting screws 21—25 enable the body 10 to be exactly adapted to the size of the needle 12, and the adjustments may be changed to correspond to a larger or smaller 110 needle, and it is necessary to change the adjustments only when the size of the needle is

changed. Thus so long as the same size needle is employed the device is in condition to be applied and the needle threaded without changing any of the adjustments.

5 When the improved device is to be used the body 10 with its attachments is forced over the needle until the latter is disposed in the socket 11 and held in position by the spring 15, the stop pin 14 enabling the device to be quickly located. Care should be taken in applying the device to see that the head 22 of the screw 21 bears against the lower face of the needle socket, and that the screw 25 bears against the presser foot head 15 27. When thus adjusted the eye of the needle is located in exact transverse alinement with the reduced aperture 18, and the needle can be readily threaded by simply passing the end of the thread into the recess 17, when the 20 converging walls of the latter will guide the thread through the eye of the needle.

To release the thread after being inserted through the eye 19, the parts of the thread at each side of the needle are grasped by the 25 thumb and forefinger of one hand and drawn downwardly against the spring holder 20 which will yield and permit the thread to pass.

The parts may be constructed of any required material and of any suitable size.

Having thus described the invention, what is claimed as new is:

1. A device of the class described comprising a body having a longitudinally directed 35 needle receiving seat in one side face and a transverse recess in the other side face, said recess converging toward one end and communicating at its contracted end with the needle seat and opening at its lower side 40 through the bottom of the body, a resilient member connected at one end to the body and unsupported at the other end and extending by its unsupported portion over the lower opening of the recess, and means for 45 retaining a needle in said seat with its eye registering with the contracted terminal of the recess.

2. A device of the class described comprising a body having a longitudinally directed 50 needle receiving seat in one side face and a

transverse recess in the other side face, said recess converging toward one end and communicating at its contracted end with the needle seat and opening at its lower side through the bottom of the body, a resilient member connected to the body and extending over the lower opening of the recess, means for retaining a needle in said seat with its eye registering with the contracted terminal of the recess, a longitudinally adjustable device connected to the body, and a transversely adjustable device connected to the body, whereby the body may be located relatively to the needle bar and the presser foot portions of a sewing machine. 55 60 65

3. A device of the class described comprising a body having a longitudinally directed needle receiving seat in one side face and a transverse recess in the other side face, said recess converging toward one end and communicating at its contracted end with the needle seat and opening at its lower side through the bottom of the body, a stop pin extending from the body adjacent to the needle seat, a resilient member connected to the body and extending over the lower opening of the recess, and means for retaining a needle in said seat with its eye registering with the contracted terminal of the recess. 70 75

4. A device of the class described comprising a body having a longitudinally directed needle receiving seat in one side face and a transverse recess in the other side face, said recess converging toward one end and communicating at its contracted end with the needle seat and opening at its lower side through the bottom of the body, a resilient member connected at one end to the body and unsupported at the other end, the unsupported portion extending over the lower opening of the recess, and a resilient holding member attached at one end to the body and extending at its free end over the needle seat and operating to yieldably support a needle in said seat with its eye registering with the contracted terminal of the recess. 80 85 90 95

In testimony whereof I affix my signature.

GEORGE B. ROWE.

Witness:

J. R. ROWLETT.
